W. F. ZIMMERMANN

CROSS RAIL GUARD

Filed March 27, 1925

UNITED STATES PATENT OFFICE.

WILLIAM F. ZIMMERMANN, OF MAPLEWOOD, NEW JERSEY, ASSIGNOR TO GOULD & EBERHARDT, OF NEWARK, NEW JERSEY, A CORPORATION OF NEW JERSEY.

CROSS-RAIL GUARD.

Application filed March 27, 1925. Serial No. 18,785.

My invention is concerned with means for protecting the guiding and bearing surfaces on a shaping machine from dirt, chips or other foreign material, and is chiefly concerned with means for protecting the surfaces of engagement between the cross head and the main frame and between the work-table saddle and the cross head.

In shaping machines, as now constructed, a reciprocating ram, which is mounted on the main frame of the machine, carries a cutting tool. A work table, which is mounted on a saddle below the cutting tool, is movable in a horizontal direction along a cross head. The cross head is movable in a vertical direction along the main frame of the machine. The chips, which are scattered over the table saddle and the cross head by the cutting tool, are not only liable to injure the surfaces of engagement between the table saddle, the cross head and the main frame but are liable to displace the position of the cross head with respect to the main frame. When the cross head is unclamped from the frame to effect vertical movement thereof, an open space is generally formed between the upper edge of the cross head and the main frame by reason of the action of the weight of the table and the cross head. If dirt or chips fall into the open space thus formed between the cross head and the frame it is difficult to clamp the cross head back into position without injury to the surfaces of engagement between the head and the frame.

One of the chief objects of my invention is to provide a guard member that shall insure against chips or dirt coming in contact with the surfaces of engagement between the table saddle, the cross head, and the main frame. The guard member also serves to protect the operating mechanism for the saddle and the cross head against chips and dirt. A guard member, which is preferably composed of sheet metal, is secured to the top of the cross head in position to extend over a portion of the work-table saddle. The guard member not only extends over a portion of the table saddle and over the cross head but also projects a short distance over each end of the cross head. The front and end edges of the guard member are bent upwardly to form flanges of very short height and the rear edge of the guard mem-

ber is bent upwardly to form a much higher flange. The rear flange is positioned adjacent to the frame of the machine and cooperates with the horizontal surface of the guard member to prevent any chips or dirt coming into contact with the surfaces of engagement between the cross head and the main frame of the machine. The end flanges of the guard member are cut away near the front edge of the member in order to permit the removal of the chips which have been collected on top of the guard member.

Near the front of the guard member is secured a yieldable means which engages the top of the table. The yieldable means is preferably a strip of leather which is riveted to the guard member. The strip of leather serves to prevent the passing of any chips and dirt under the guard member to injure the above mentioned surfaces of engagement.

Other objects and advantages will be in part indicated in the following description and in part rendered apparent therefrom in connection with the annexed drawings.

To enable others skilled in the art so fully to apprehend the underlying features hereof that they may embody the same in the various ways contemplated by this invention, drawings depicting a preferred typical construction have been annexed as a part of this disclosure and, in such drawings, like characters of reference denote corresponding parts throughout all the views, of which:

Figure 1 is an end elevational view of a shaping machine constructed in accordance with my invention. Fig. 2 is a front view, on an enlarged scale, of a portion of the machine shown in Fig. 1. Fig. 3 is a sectional view of a portion of the guard member.

Referring to the drawing a shaping machine is illustrated comprising a base 1 upon which is mounted a main frame 2. The main frame 2 carries a reciprocating ram 3 which in turn carries a tool head 4. The ram 3 is reciprocated in any conventional manner and the stroke thereof may be varied as desired in accordance with usual practice. A cross head 5, which supports a work-table saddle 6 is secured to the end face of the main frame 2. The saddle 6 carries a work-table 6^a and the table car-

ries the work 30. As illustrated in the drawings the cross head 5 is secured to the main frame 2 by means of strips 7 and bolts 8, one only of each is illustrated on the drawing. The vertical movement of the cross head 5 on the main frame 2 is effected by means of a screw shaft 9. The screw shaft 9 may be controlled or rotated in any conventional manner. Before any movement of the cross head 5 can be effected on the main frame, it is necessary to unclamp the cross head by loosening the bolts 8. Upon unclamping the cross head, it is apparent the weight of the table 6 and the cross head 5 tends to form an open space between the upper edge of the cross head and the main frame. If no means is provided for protecting the surfaces of engagement between the cross head and the main frame, chips and dirt will collect in such open space between the cross head and the main frame whenever the cross head is unclamped to effect vertical movement thereof.

The work carrying table 6^a and the saddle 6 are not only supported on the cross head 5 but are guided by means of surfaces formed on such cross heads. A hook portion 10 of the saddle 6, which projects over the part 12 of the cross head, not only rests on a bearing surface formed on the cross head but also engages a wedge member 11 at the rear of the part 12 of the cross head. Moreover, a guide surface is formed on the cross head near the lower part thereof and bearing surfaces are formed on the front thereof. It is very desirable and essential for good operation of the machine to prevent chips or dirt from injuring such bearing and guide surfaces.

A guard member 15, which is preferably composed of sheet metal such for example, sheet steel, is secured to the top of the cross head 5 by means of bolts 16. Suitable spacing members or washers 17 are placed between the top of the cross head and the guard member in order to hold such guard member above the top of the table saddle 6. A flat horizontal portion 18 of the guard member projects completely over the cross head 5 and over a portion of the work table saddle in order to cover all of the above mentioned guide and bearing surfaces. Moreover, the horizontal surface 18 extends somewhat beyond the ends of the cross head 5 in order to protect the mechanism which is mounted on one end of the cross head 5 for effecting movement of the head and feeding movements of the work carrying table 6^a. The front edge of the guard member is bent upwardly to form a flange 19 and the end edges thereof are bent upwardly in like manner to form flanges 20. The end flanges 20 are cut away at 21 in order to permit the easy removal of any chips which may be collected on the horizontal surface 18. The

rear edge of the guard member is bent upwardly to form a flange 22 which is much higher than the flange 19 at the front of the guard member and the flanges 20 at the ends thereof. The flange 22 is positioned adjacent to the main frame 2 of the machine and cooperates with the horizontal surface 18 to prevent any chips coming in contact with the surfaces of engagement between the frame and the cross head. An opening 23 is formed on the horizontal surface 18 of the guard member to permit the screw shaft 9 to pass therethrough when the cross head is near its lowermost position. The opening 23 in the guard member is covered by means of a casing or box 24 which is secured to the guard member in any suitable or convenient manner. The casing 24 serves to protect the screw shaft 23 from chips irrespective of the crosshead position.

Near the front of the guard member 15 is mounted a yielding means 26 which serves to close the opening between the guard member and the table saddle 6. The yielding means 26 is preferably a leather strip which is riveted to the horizontal surface 18. The leather strip 26 is always in engagement with the work-table saddle 6 and prevents chips from passing under the guard member, as indicated in Fig. 3 of the drawing. The resiliency of the guard member, which is composed of sheet metal, and the yielding nature of the leather insures a firm engagement between the leather and the table saddle to prevent any chips from passing under the guard member. It should also be noted that the yielding nature of the strip 26 eliminates the necessity of accurately aligning the guard member with the top of the work-table saddle.

Without further analysis, the foregoing will so fully reveal the gist of this invention that others can, by applying current knowledge, readily adapt it for various utilizations by retaining one or more of the features that, from the standpoint of the prior art, fairly constitute essential characteristics of either the generic or specific aspects of this invention and, therefore, such adaptations should be, and are intended to be, comprehended within the meaning and range of equivalency of the following claims.

Having thus revealed this invention, I claim as new and desire to secure the following combinations and elements, or equivalents thereof, by Letters Patent of the United States:—

1. In a shaping machine having a cross head mounted on the main frame and a table saddle movable along the cross head, the combination comprising a guard member, located above the cross head; a raised flange formed on the rear edge of the guard member, said flange being positioned adjacent to the machine frame; and a leather strip se-

cured to the front lower surface of the guard member and engaging the top of the table saddle.

2. In a shaping machine having a cross head mounted on the main frame and a table saddle movable along the cross head, the combination comprising a guard member extending over the cross head and a portion of the table saddle; a raised flange formed on the rear edge of the guard member and positioned adjacent to the frame of the machine; and a yieldable member secured to the bottom surface of the guard member and engaging said table saddle.

15 3. In a shaping machine having a cross head mounted on the main frame, a table saddle movable along the cross head, and a screw shaft for moving the cross head, the combination comprising a guard member mounted on the cross head and extending over the cross head and a portion of the table saddle; a casing mounted over said guard member for receiving the end of said screw shaft; and a yielding member secured 25 to the bottom surface of the guard member for engaging the top of said table saddle.

4. In a shaping machine, the combination comprising a cross head movable vertically along the main frame of the machine; a screw shaft for moving the cross head; a work table saddle movable along the cross head; a guard member secured to the top of the cross head and having a raised flange positioned adjacent to the frame of the machine; a casing mounted over an opening formed in said guard member for receiving the end of said screw shaft when the cross head is in a lower position; and yielding means secured to the lower front surface of 35 the guard member and engaging said table saddle.

5. In a shaping machine, the combination comprising a cross head movable with respect to the main frame of the machine; a work table saddle movable along the cross head; a guard member secured to the top of the cross head and extending over the table saddle, and yielding means secured to the guard member and engaging the table saddle.

50 6. In a shaping machine, the combination comprising a cross head movable along guide ways formed on the main frame of the machine; a work-table saddle movable along the cross head; a guard member secured to the top of the cross head and extending over the table saddle and formed to exclude 55 chips from the surface of engagement between the cross head and the main frame;

and yielding means positioned between the guard member and the table saddle.

60 7. In a shaping machine, the combination comprising a cross head movable along guideways formed on the main frame of the machine; a work table saddle movable along guideways on the cross head and having bearing surfaces thereon; a guard member secured to the top of the cross head and extending over the table saddle and formed to exclude chips from the surfaces of engagement between the cross head, the main frame, and the table; and yielding means positioned between the guard member and the table saddle.

75 8. In a shaping machine, the combination comprising a cross head having vertical movement on the main frame of the machine; a vertical screw shaft engaging said cross head for effecting vertical movement thereof; a work table saddle movable along said cross head, said table being movable 80 along guideways formed on the cross head and said head being movable along guideways formed on the frame; a guard member secured to the top of the cross head and extending over guideways formed on the frame and on the cross head; and yielding means secured to the guard member and engaging the top of the table saddle to keep 85 chips and dirt from the guide and bearing surfaces between the frame, the cross head and the table saddle.

90 9. In a shaping machine, the combination comprising a cross head having vertical movement on the main frame of the machine; a vertical screw shaft engaging said cross head for effecting vertical movement thereof; a work table saddle movable along said cross head, said table saddle being movable along guideways formed on the cross head and said head being movable along 95 guideways formed on the frame; a guard member secured to the top of the cross head and extending over guideways formed on the frame and on the cross head, said member having a casing mounted thereon to receive and cover the end of the screw shaft for moving the cross head; and yielding means secured to the guard member and engaging the top of the table to keep chips and dirt from the guide and bearing surfaces between the frame, the crosshead and the table saddle.

100 105 110 In witness whereof, I have hereunto subscribed my name.

WILLIAM F. ZIMMERMANN.
